DESIGN FOR A PINAFORE

Ellen Brooke, New York, N. Y., assignor to Mirer
and Cooper, a copartnership

Application November 18, 1944, Serial No. 116,431

Term of patent 7 years

(Cl. D3—26)

To all whom it may concern:

Be it known that Ellen Brooke, a citizen of the United States and residing in the city, county, and State of New York, has invented a new, original, and ornamental Design for Pinafores, of which the following is a specification, reference being had to the accompanying drawing, forming a part thereof in which:

Fig. 1 is a plan view of the pinafore showing my new design.

Fig. 2 is a front elevational view of the pinafore, and

Fig. 3 is a rear view of Fig. 2.

I claim:

The ornamental design for a pinafore, substantially as shown.

ELLEN BROOKE.
